JUG

Torsti O. Matson, West Townsend, Mass., assignor to Foster Grant Co., Inc., Leominster, Mass., a corporation of Delaware

Filed Aug. 15, 1960, Ser. No. 61,771

Term of patent 14 years

(Cl. D58—17)

FIG. 1 is a front perspective view of a jug showing my new design;

FIG. 2 is a side elevational view thereof; and

FIG. 3 is a cross-sectional view thereof taken on the line 3—3 of FIG. 1.

The dominant feature of my design resides in the portions shown in full lines.

The side not shown is the same as the side shown.

I claim:

The ornamental design for a jug, substantially as shown and described.
